FLUID PRESSURE CONVERTER

John S. Eubanks, Box 182, Salyer, Calif.

Filed Oct. 17, 1958, Ser. No. 767,898

3 Claims. (Cl. 103—123)

This invention relates to fluid pressure conversion devices, and more particularly to a fluid pressure converter of the type having a rotary piston member engaged by reciprocating sealing means defining respective working chambers on the opposite sides thereof.

A main object of the invention is to provide a novel and improved fluid pressure converter which may be employed as a fluid motor, pump, or other fluid pressure conversion apparatus, the device being simple in construction, involving relatively few parts, and providing efficient conversion of fluid pressure therein.

A further object of the invention is to provide an improved fluid pressure converter which may be employed efficiently as a motor or pump, the converter being inexpensive to fabricate, being durable in construction, being relatively compact in size, and being easily reversible.

A still further object of the invention is to provide an improved fluid pressure converter which may be embodied as a compressed air, gas or steam driven motor.

Further objects and advantages of the invention will become apparent from the following description and claims, and from the accompanying drawings, wherein:

Figure 1 is a perspective view of a fluid pressure converter constructed in accordance with the present invention, adapted to be employed, for example, as a motor.

Figure 2 is an enlarged vertical cross sectional view taken on the line 2—2 of Figure 1.

Figure 3 is a vertical cross sectional view taken on the line 3—3 of Figure 2.

Figure 4 is a horizontal cross sectional view taken on the line 4—4 of Figure 3.

Figure 5 is an enlarged cross sectional detail view taken on the line 5—5 of Figure 3.

Figure 6 is an enlarged perspective view, showing one of the sealing plates employed in the fluid pressure motor of Figures 1 to 5, also showing one of the associated follower members and resilient connecting means associated therewith, shown separated from the sealing plate.

Figure 7 is a cross sectional view taken on the line 7—7 of Figure 4.

Referring to the drawings, 11 generally designates a fluid pressure converter according to the present invention, adapted to be used as a fluid pressure-operated motor, and illustrating one of the applications of the converter. Thus, the fluid motor 11 comprises a housing 12 consisting of a generally oval main body 13 to which are secured the respective front and rear end plates 14 and 15. The main body 13 is formed with a cylindrical bore 16, said bore being countersunk at its ends to define the annular recesses 17 and 18 which snugly receive the thickened main body portions 19 and 20 of the respective front and rear end plates 14 and 15, as is clearly shown in Figure 2. The peripheral portions of the end plates 14 and 15 are secured to the end surfaces of the main body 13 by suitable fastening bolts 21, as shown in Figure 2.

Designated at 22 is a rotor member of generally

2

polygonal cross sectional shape, for example, having a cross section shaped generally as an equilateral triangle, as shown in Figure 3, the rotor comprising the respective corner portions 23 and the flat plane faces 24 connecting the corner portions. The corner portions 23 have arcuate surfaces 25 concentric with the cylindrical bore 16, said arcuate surfaces 25 being located closely adjacent to the cylindrical inside surface of the bore 16, as shown in Figure 3 so as to be almost in sliding contact therewith.

Thus, the arcuate surfaces 25 are so close to the cylindrical inside surface of the cavity in body 13 as to define fluid-retaining chambers therebetween.

Rotor 22 is secured on a supporting shaft 26 which is suitably journaled in the front and rear end plates 14 and 15 so as to support the rotor 22 for rotation on the axis of the cylindrical bore 16. The end surfaces of rotor 22 are substantially in sliding and sealing contact with the inside surfaces of the thickened portions 19 and 20 of the front and rear end plates 14 and 15.

As above mentioned, the body 13 is generally oval or elliptical in cross sectional shape. Formed on the major diameter of the body are respective opposed passages 27 and 27' which extend in a plane containing the axis of bore 16 and which are coextensive in length with the rotor 22, the passages 27 opening into the cylindrical bore 16 and thus being directed radially relative to the rotor 22. Slidably mounted in the passages 27 and 27' are the respective sealing plates 28 and 28', said plates sealingly and slidably engaging the thickened wall portions 19 and 20 at their end edges 29, 29 and being formed with axially extending sealing edge portions 30 which are slidably and sealingly engageable with the peripheral surface of rotor 22. As shown in Figures 4 and 5, the thickened wall portions 19 and 20 of the end plates 14 and 15 are formed with guide grooves 31 which receive the respective marginal end portions of the sealing plate 28. The grooves 31 are of sufficient length to allow the sealing plates 28 to reciprocate as said plates follow the contour of the rotor 22 when said rotor revolves.

Rotor 22 is formed on its opposite ends with respective grooves 33, said grooves generally following the contour of the rotor and being located adjacent the margins of the end portions of the rotor, as shown in Figure 3. Respective pairs of follower rollers 34, 34 and 34' are engaged in the grooves 33 on the opposite end surfaces of the rotor 22, said follower rollers being resiliently connected to the respective sealing plates 28 and 28'. Thus, the rollers are journaled to respective connecting bars 35 which extend through the grooves 33 between spaced fingers 36, 36 formed at the side margins of the plates 28, 28', the connecting rods 35 extending into enlarged rectangular recesses 37 formed in the side edges of the sealing plates. A retaining nut 38 is threaded on the end of each rod 35, and a coiled spring 39 surrounds the rod, bearing between the retaining nut 38 and the shoulders 60, 60 defined on the fingers 36, 36 at the inner ends of the recesses 37. The coiled springs 39 thus bias the sealing plates 28, 28' into sealing engagement with the peripheral surface of rotor 22.

As shown in Figure 3, the grooves 33 are generally triangular in configuration and may be suitably arcuately inwardly curved and otherwise spaced with respect to the peripheral surface of the rotor 22 to provide variations in the tension developed in the coiled springs 39 as the rotor 22 revolves, to accordingly vary the sealing pressure exerted by the springs on the sealing plates 28 and 28' in accordance with the amount of extension of said plates 28 and 28' from their associated guide recesses 27 and 27'.

As will be readily apparent, the sealing plates 28, 28' are reciprocated responsive to rotation of the rotor 22, but said plates are held substantially in sealing contact

with the peripheral surface of the rotor by the force of the coiled springs 39.

Designated at 40 is a passage formed in the wall of body 13, said passage extending through the body wall and opening into the space in the cavity 16 on one side of sealing plate 28. A fluid outlet passage 41 is formed in the wall of body 13, extending through said wall and opening into the space in cavity 16 on the side of sealing plate 28 opposite the space communicating with passage 40. A further passage 42 is formed in the wall of body 13 between the passages 40 and 41, communicating with the outer end of sealing plate passage 27. The stem of a T-fitting 43 is connected to the end of passage 40, and an angle fitting 44 connects the end of passage 42 to one branch of the fitting 43. A fluid supply conduit 45 is connected to the other branch of T-fitting 43, whereby supply fluid under pressure may be simultaneously admitted into passage 40 and at the same time exert fluid pressure on the end of sealing plate 28. An angle fitting 46 is connected to the end of passage 41, and connected to the fitting 46 is the fluid outlet conduit 47. Thus, the fluid under pressure admitted from the supply conduit 45 enters the cavity 16 in the space above the sealing plate 28, as viewed in Figure 3, exerting force on the face 24 of the rotor 22 which urges the rotor in a clockwise direction, as viewed in Figure 3, causing clockwise rotation of said rotor, whereby the load connected to the rotor shaft 26 may be driven.

At the side of body 13 opposite the sealing plate 28 respective fluid inlet and outlet passages 40' and 41' are provided, as well as an intermediate passage 42' communicating with the outer end of the sealing plate guide passage 27'. A T-fitting 43' has its stem portion connected to the passage 40' and has one branch thereof connected by an angle fitting 44' to the passage 42'. A pressure fluid supply conduit 45' is connected to the remaining branch of the fitting portion 43', whereby fluid under pressure may be simultaneously admitted to the passage 40' and the passage 42'. An angle fitting 46' connects the passage 41' to a discharge conduit 47'.

In operation, fluid under pressure enters each of the passages 40 and 40', at the same time exerting sealing pressure on the respective sealing plates 28 and 28' by their connections with the sealing plate passages at the conduit passages 42, 42'. The fluid under pressure enters the cavity 16, acting on the faces 24 of rotor 22, and causing the rotor to move in a clockwise direction, as viewed in Figure 3. Fluid from the supply passage 40 ultimately discharges through the exhaust passage 41' and exhausts through conduit 47'. Fluid from the passage 40' ultimately discharges through passage 41 and conduit 47. The sealing plates 28 and 28' engage the peripheral surface of the rotor 22, defining a working space on one side of each sealing plate and a discharge space on the other side thereof.

As will be readily apparent, the direction of rotation of rotor 22 may be reversed by reversing the inlet and outlet connections thereof, namely, by connecting the fluid supply conduits to the passages 41, 41' and the fluid discharge conduits to the passages 40, 40', the intermediate passages 42 and 42' being connected to the fluid supply conduits so as to provide the auxiliary sealing forces on the sealing plates 28, 28'.

While the apparatus described above has been discussed as a motor, whereby fluid pressure is converted into mechanical force, obviously the apparatus may be employed as a pump by connecting a suitable prime mover to the rotor shaft 26 and connecting the conduits 47, 45 and 47', 45' in the fluid lines requiring pressure conversion. Thus, assuming the rotor 22 to rotate clockwise, pressure will be developed in the spaces communicating with the outlet passages 41', 41 and suction will be developed in the inlet passages 40, 40'. Under these conditions, the intermediate passages 42, 42' should be connected respectively to the passages at maximum

pressure, namely, the output passages 41', 41, whereby the output pressure is utilized to provide the auxiliary sealing force on the sealing plates 28, 28'.

It will be readily apparent that the fluid converter may be designed with a rotor having any desired number of lobes, namely, having any desired polygonal cross sectional shape. In each case sealing plates will be provided to define working spaces on opposite sides thereof in the manner described in connection with the specific embodiment of the invention illustrated in the drawings and above described. For example, the rotor may have an odd number of lobes and an even number of sealing plates, or conversely, the rotor may have an even number of lobes and an odd number of sealing plates. This arrangement will always provide an overlap of power impulses, insuring smooth operation.

In the specific application above described and illustrated in the drawings, the fluid pressure acting on the outer ends of the sealing plates 28 and 28' develops forces acting on the faces of the rotor 22, assisting the rotation of said rotor. The camming action of the sealing plates is effective during the initial portion of sealing contact with the spaces 24 to develop force assisting rotation of the rotor, and continues until the sealing plates 25 engage the mid portions of the faces 24. For example, this condition is illustrated in Figure 3, wherein the sealing plate 28 engages the mid portion of the face 24 at the left side of rotor 22. Under these conditions the space above the sealing plate 28 receives fluid under pressure which acts against approximately one-half the area of face 24 and thus develops sufficient force to maintain rotation of rotor 22 until the sealing plate 28 engages the next rotor face 24 and again develops camming force on the rotor. It will thus be apparent that the fluid pressure is transmitted to the rotor not only by the direct action thereof against the faces 24 of the rotor but also by the transmission of camming force on the rotor by the action of the sealing plate 28 against the rotor faces as the angle between the sealing plates changes from the relatively small value occurring when the sealing plates first engage the faces 24 until said sealing plates are substantially at right angles to said faces.

As will be further understood, the device of the present invention may be employed with any suitable fluid. For example, the device may be constructed as a compressed air, gas or steam-driven motor.

While a specific embodiment of a fluid pressure converter has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A fluid pressure converter comprising a housing having a cylindrical inner cavity, a rotor member of generally polygonal shape in said cavity and having corner portions thereof located closely adjacent to the cylindrical inner cavity surface and having substantially flat plane surfaces extending chordally in said cavity between said portions, means rotatably supporting said rotor member for rotation on the axis of said cavity, said housing being formed with a guide recess opening into said cylindrical cavity and directed toward said rotor member, a sealing plate slidably mounted in said guide recess and being extensible therefrom, said sealing plate having an edge sealingly engaging the peripheral surface of said rotor member, said housing being formed in its peripheral wall with a first fluid passage extending through said wall and communicating with the space in the cavity on one side of sealing plate and with a second fluid passage extending through said wall and communicating with the space in the cavity on the other side of said sealing plate, an end surface of said rotor member being formed with a groove extending along the periph-

eral margin of said rotor member, follower means engaging in said groove, and means yieldably connecting said follower means to said sealing plate to urge said plate inwardly against said peripheral surface of the rotor member, said groove being inwardly arcuately curved between said corner portions and being constructed and arranged to vary the inward force on said sealing plate in accordance with the amount of extension of said sealing plate from said guide recess.

2. A fluid pressure converter comprising a housing having a cylindrical inner cavity, a rotor member of generally polygonal shape in said cavity and having corner portions thereof located closely adjacent to the cylindrical inner cavity surface and having substantially flat plane surfaces extending chordally in said cavity between said portions, means rotatably supporting said rotor member for rotation on the axis of said cavity, said housing being formed with a guide recess opening into said cylindrical cavity and directed toward said rotor member, a sealing plate slidably mounted in said guide recess and being extensible therefrom, said sealing plate having an edge sealingly engaging the peripheral surface of said rotor member, said housing being formed in its peripheral wall with a first fluid passage extending through said wall and communicating with the space in the cavity on one side of said sealing plate and with a second fluid passage extending through said wall and communicating with the space in the cavity on the other side of said sealing plate, conduit means connecting one of said fluid passages to the outer end portion of said guide recess, whereby fluid under pressure in said conduit means will exert inward force on said sealing plate, urging the sealing plate inwardly against a peripheral surface of the rotor member, an end surface of said rotor member being formed with a groove extending along the peripheral margin of said end surface, follower means engaged in said groove, and means resiliently connecting said follower means to said sealing plate to further urge said plate inwardly against the peripheral surface of said rotor member, said groove being inwardly arcuately curved between said corner portions and being constructed and arranged to vary the inward force on said sealing plate in accordance with the amount of extension of said sealing plate from said guide recess.

3. A fluid pressure converter comprising a housing having a cylindrical inner cavity, a rotor member of generally polygonal shape in said cavity and having corner

portions located closely adjacent to the cylindrical inner cavity surface and having substantially flat plane surfaces extending chordally in said cavity between said corner portions, means rotatably supporting said rotor member for rotation on the axis of said cavity, said housing being formed with a guide recess opening into said cylindrical cavity and being coplanar with said axis and directed toward said rotor member, a sealing plate slidably mounted in said guide recess and being extensible therefrom, said sealing plate having an edge sealingly engaging the peripheral surface of said rotor member, said housing being formed in its peripheral wall with a first fluid passage extending through said wall and communicating with the space in the cavity on one side of said sealing plate and with a second fluid passage extending through said wall and communicating with the space in the cavity on the other side of said sealing plate, conduit means connecting one of said fluid passages to the outer end portion of said guide recess, whereby fluid under pressure in said conduit means will exert inward force on said sealing plate, urging the sealing plate cammingly against the peripheral surface of the rotor member, an end surface of said rotor member being formed with a groove extending along the peripheral margin of said end surface, follower means engaged in said groove, and means resiliently connecting said follower means to said sealing plate to further urge said plate inwardly and sealingly against the peripheral surface of said rotor member, said groove being inwardly arcuately curved between said corner portions and being constructed and arranged to vary the inward force on said sealing plate in accordance with the amount of extension of said sealing plate from said guide recess.
